UNITED STATES PATENT OFFICE.

FREDERICK C. WILLIAMS, OF SAN FRANCISCO, CALIFORNIA.

PENCIL MARKING AND VENDING MACHINE.

1,023,540.

Specification of Letters Patent.

Patented Apr. 16, 1912.

Application filed January 27, 1910. Serial No. 540,369.

To all whom it may concern:

Be it known that I, FREDERICK C. WILLIAMS, a citizen of the United States, residing in the city and county of San Francisco and State of California, have invented new and useful Improvements in Pencil Marking and Vending Machines, of which the following is a specification.

This invention relates to a marking and vending machine, and particularly to a coin-operated vending machine in which lead, pencils, pen-holders and like articles are marked or printed upon before delivery.

It is the object of this invention to provide a vending machine which requires the use of a coin, slug, or other token in its operation, the function of which is to vend a variety of styles or grades of pencils or the like.

20 A further object is to provide means by which the operator or patron can mark the article to be vended before it is discharged from the machine with words or characters.

25 Another object is to provide a machine of the above description, which is simple in construction and positive in operation.

The invention consists of the parts and the construction and combination of parts as hereininafter more fully described and 20 claimed, having reference to the accompanying drawings, in which—

Figure 1 is a side view of the invention, with casing and other portions broken away, showing the parts in a normal position.

35 Fig. 2 is a front view, with casing removed and partly in vertical section. Fig. 3 is a detail of a type segment. Fig. 4 is a sectional detail of the coin chute. Fig. 5 is a detail in perspective of the inking roller 40 and pencil carriage. Fig. 6 is a fragmentary detail of the type setting keys.

In the drawings, A is the bed-plate on which the machine is mounted, and which may be of any suitable construction. This 45 bed-plate forms the bottom of a casing A', in which the machine is designed to be inclosed, which casing may be of any desired design, but not necessary to be shown in full in the drawings.

50 Standards 2 are mounted on the bed-plate A, through which a horizontally disposed shaft 3 extends. This shaft 3 is arranged transversely across the machine, and in addition to the support it receives in the standards 2, is further carried in the sides of the inclosing casing A'. One end of the shaft 3

is provided with a crank or handle 4, by means of which the shaft may be rotated a limited distance in either direction, as later described.

60 A sleeve 5 is mounted on the shaft 3 and extends between the standards 2, as shown in Fig. 2, a flange 6 on one end of the sleeve 5 being secured to the standard 2 so as to prevent the rotation of the sleeve.

65 A number of type-carrying disks or segments 7 are loosely mounted on the sleeve 5, between the standards 2, a portion of the peripheries of each segment being provided with characters or type 7'—7^a as shown in Fig. 3.

70 There are two sets of type or printing characters on the periphery of each disk or segment, one set 7' on the forward portion of the segment arranged in order from the front end of the segment back to about 75 its center, and the other or rear set 7^a, which are the printing characters are arranged in order from near the center of the segment back to its rearward portion. The latter

set of characters are reversed, as shown in Fig. 3, so as to give an imprint that will 80 show the characters in their proper positions. The forward set of characters being employed for reading purposes only are arranged in the usual manner. In this case

85 sixteen type-carrying segments are employed, each of which corresponds to the other, and each having two complete alphabets arranged on its periphery as just described.

90 A thumb-key 8 is secured to each segment 7, and projects outside of the machine casing A' through a suitable slot. Each segment 7 can be rotated on its bearing so as to adjust the position of the printing type 95 thereon in alinement on the printing line by moving a thumb-key 8. A spring 9 is interposed between each key 8 and the casing A' in such a manner as to act as a brake, the tension or friction of which is sufficient to momentarily retain the thumb-key and its corresponding segment in any 100 position to which it may be moved on its hub. Normally the type segments and thumb keys stand in the position shown in Fig. 1, with the foremost letters 7' of the forward sets of characters 7' registering with a slot 10 in the casing A', and the forward letters of the rearward sets of type characters 7^a in alinement at the highest 105 point 11 of the segments, which is termed the printing point. An ink pad 12 is dis-

posed above the segments 7 at a point forward of the printing point 11, upon and across which an inking roller 13 is adapted to pass. The inking roller 13 is provided with an axle at each end which extends through a slot in the upper end of the arms 14, which are disposed outside of the standards 2, and are loosely mounted at their lower ends on the shaft 3. Springs 15 exert a downward pull on the inking roller 13, and tend to retain the latter in close contact with the ink pad 12, and a spring 16 tends to retain the arms 14 in the position shown in Fig. 1, with the inking roller 13 on the ink pad 12. The inking roller 13 is caused to move across the ink pad 12, and over the exposed portion of the type segments 7 on the printing line 11 by means of a lever arm 17, pivoted at 18 to the standard 2, and actuated by a projection 19, on the shaft 3, as later described. The upper end of the lever-arm 17 contacts a pin 20 on the ink roller carrying arms 14, and is retained in contact therewith by means of a spring 20', which extends between the lever-arm 17 and the arm 14.

As a means of insuring that the type on the segment 7 will not be moved out of alinement at the printing line 11, by the impact of the inking roller 13, or by any other reason, during the operation of the machine, the segments are provided on their rearward portion with regular notches or teeth 21, corresponding to the number of printing characters on the peripheries of the segments. A bar 22 extends across the toothed portions of the segments, and is supported at each end on an arm 23, pivoted at 24 to the standards 2, and is normally held out of contact with the teeth 21 by means of a spring 25 which extends between the arm 23 and a stud 26 on the shaft 3. When the latter is revolved so as to move the stud 26 forward, the bar 22 is brought into engagement with the teeth 21, and is retained therein until the shaft 3 returns to its original or normal position as later described, the spring 25 permitting of the stud 26 continuing its forward movement after the arms 23 have come to rest.

The pencils or like articles to be printed upon and vended are placed in a horizontal position in vertical racks or guides 28, arranged transverse to and above the rear portion of the segments 7, the lowermost pencil in each rack 28 resting upon a releasing device (later described), by means of which the pencil may be delivered to inclined guides 29 down which the selected pencil is adapted to roll toward the printing line 11.

As a means of insuring that the pencil be deposited in true alinement with the type on the printing line 11, a carriage 30 is mounted on the inking roller arms 14 in such manner as to travel therewith, the extended portion

of the carriage, being supported and slideable upon the horizontally projecting portions 2' of the standards 2. Upwardly projecting members 30' on the carriage 30 stop the downward movement of the pencil at the lower end of the inclined guides 29, and as the carriage 30 moves backward the pencil is shoved back up the inclined guides until the projections 30' pass under the pencil, whereupon the latter continues down and drops over the end of the inclined guides on to the carriage 30, in front of the projections 30'. In this manner the pencil is kept clear of the printing line 11 until after the inking roller 13 has performed its function, and as the latter returns to its normal position on the ink-pad 12, the pencil is brought forward over the printing line 11 by the members 30' on the carriage 30.

The pencil is pressed upon the printing characters by means of an impression bar 31 which is mounted upon arms 32, pivoted at 33, the bar 31 being actuated through a link-bar 34 which is pivoted at one end to the impression bar 31, and to a lug 35 on the shaft 3 at the other end, in such manner that as the shaft 3 is rotated in the direction of the arrow Z, Fig. 1, the impression bar will be drawn downward so as to bear against the pencil to be printed, and press it firmly upon the printing-type, so as to print and impress thereon the characters previously "set up" or arranged on the printing line. The under side of the impression bar 31 is grooved as at 36, which groove is adapted to conform to the pencil, and further insure the latter being held in alinement with the printing line.

The pencil releasing mechanism is constructed as follows: The lowermost pencil in each rack 28, has its ends supported between two of the radial projections of star-shaped members 38 which are mounted on horizontally disposed shafts 37 extending across the machine beneath each of the pencil racks 28. The outer end of each shaft 37 is provided with a five-toothed ratchet 39, rigidly mounted thereon, and adapted to be rotated by means of a pawl 40 carried by an arm 41 loosely mounted on each shaft 37. A link 42 connects each arm 41 to the lower end of a rocking lever 43, pivoted on a shaft 44. The upper end of each lever 43 is adapted to be tilted backward by means of a coin cylinder 45, as later described, so as to pull the arm 41 forward and, by reason of the pawl 40, rotate a shaft 37 a sufficient distance to allow the lowermost pencil to fall from the star-shaped member 38 to the inclined guides 29, and permit the next pencil above in the rack 28 to fall between the next space between the radial projections of the members 38. A spring 43' acts to restore the lever 43 and its connections to the

normal position shown in Fig. 1. The coin top or cylinder 45 is mounted in the frame of the machine and is adapted to be rotated by means of a crank handle 46. The cylinder 45 extends horizontally in front of the upper ends of the rocking levers 43, the latter projecting into circumferential slots 47 formed in the cylinder. A longitudinal slot or pocket 48 is disposed at right angles to each slot 47 in the cylinder 45, and is of such dimensions as to readily accommodate a coin, usually a five-cent piece, which may be dropped therein through a suitable slot, not shown, in the machine casing A'. A coil spring 49, is attached to and wound on the cylinder 45, and connects with the stationary frame of the machine, and normally tends to retain the cylinder in the position shown in Fig. 1, with the socket 48 registering with the coin slot in the casing A'.

The operation of the mechanism of the invention so far described is as follows: The patron or operator first sets up or adjusts the position of the type characters on the printing line 11, by rotating the type segments 7 by means of the thumb keys 8, as before described, the operator determining which characters are on the printing line by the characters exposed in the slot 10. A coin is then inserted in the coin slot 48 in the cylinder 45, corresponding to the grade of pencil selected, and the cylinder turned by means of the crank 46. The coin being transversely disposed across the circumferential slot 47, its upper edge contacts and presses the upper end of the corresponding rocking lever 43 backward thereby releasing the selected pencil as before described. The pencil slides down the inclined guides 29 as before mentioned, as soon as released. The cylinder 45 is here momentarily arrested and prevented from returning to its normal position, so as to prevent the operator from releasing another pencil with the same coin, and also prevent the insertion of other coins until the function of the machine has been performed. This is accomplished by means of a pawl 50 which engages a ratchet or tooth 51 on the cylinder 45, which temporarily prevents the return of the cylinder 45, and at the same time permits the coin to fall out of the coin slot 48 into a chute 52, which leads to any suitable bank not shown. The operator then pulls the crank handle 4 forward, which action causes the shaft 3 to rotate in the direction of the arrow Z, Fig. 1, the projection 19 contacting the short end of the lever-arm 17, so as to rock the latter and cause the inking roll 13 and carriage 30 to move across the printing line 11 as before described. The inking roll 13 and carriage 30 are returned to their normal position by the spring 16, as soon as the projection 19 is released from the lever-arm. The pencil has now been brought forward by the car-

riage 30, and is supported on the latter just above the printing line 11. Continued pull on the hand-lever 4 draws the impression bar downward as hereinbefore disclosed so as to imprint the desired characters thereon.

This forward movement of the shaft 3 also releases the pawl 50 from the cylinder 45 by reason of an extensible connection 53 which connects the former with the latter as shown in Fig. 1. The cylinder 45 is then returned to its normal position by means of the spring 49. The handle 4, being carried to the limit of its forward movement, which may be any desired form of stop, not shown, the operator then returns it to its normal position shown in Fig. 1. The backward or return stroke of the lever restores the impression bar 31, and the projection 19, to their normal position in readiness for another operation, and at the same time operates certain mechanism for discharging the printed pencil from the machine and restores the type-carrying segments to their normal position.

The pencil is removed by means of a rocking-arm 54, pivotally mounted at its lower end, and provided with a head at its upper end which is adapted to contact the end of a pencil and shove it forward to the outside of the machine, as follows: A cam 55 is mounted on the shaft 3, one side of which is on a plane at right angles to the axis of the shaft, and the other side is disposed at an angle thereto, in such manner that as the shaft moves on the forward stroke, the projecting roller 56 on the arm 54 travels along the straight side of the cam, thereby retaining the arm 54 in its rearward position, and tending to buckle the spring 57. When the shaft 3 completes its forward movement, the roller 56 passes beyond the end of the cam 55, the spring 57, in straightening, carrying the arm 54 sufficiently forward, so that as the shaft 3 returns on its backward movement, the roller 56 is engaged by the angular or inclined side of the cam 55 which carries the upper end of the rocker arm 54, forward, so as to shove the pencil out through a suitable opening in the casing A' not shown. The spring 57, being distended, when the widest end of the cam 55 is reached, it restores the arm to the position shown in Fig. 1, in readiness for another operation. A like cam 58 on the shaft 3, acts in a similar manner upon a bell-crank lever 59 so as to rock a lever 60, loosely fulcrumed on the shaft 3. The short end of the lever 60 is engaged by the bell crank 59, and the other end carries a horizontal portion 60' which extends across the machine beneath the forward portion of the type-carrying segments 7. When the short arm of the lever 60 is carried downward by the bell crank 59 on the return of the shaft 3, the outer end of the lever 60 and the portion 60'

are raised upward so as to lift the segments 7 back to their normal position, shown in Fig. 1.

Any suitable disposition of the coins may 5 be made after leaving the coin-head or cylinder 45, as desired, but I prefer to subject them to the following described device for detecting slugs, spurious coins, and the like. The coin chute 52 is provided at any 10 suitable point with a rocking lever 61 mounted on and pivoted to the back of the chute. The short arm of the lever is bifurcated, each fork being provided with a flange which extends through a slot in the chute, 15 as shown in Fig. 4. The lower fork and flange 62 normally projects in the path of the coin so as to temporarily prevent it passing on to the bank, the upper fork and flange 63 extending into the chute rearward 20 of and above the coin held by the flange 62. The long arm 61 is connected by a wire 64 to a bell crank 65, Fig. 1 the long arm of which has a projection 66 which extends across and forward of the lower portion of 25 the rocking levers 43, in such manner that as any one of the latter is rocked, an upward pull will be transmitted to the long arm of the bifurcated lever 61 through the bell crank 65. This action causes the flange 30 62 to be lowered out of the path of the lowermost coin and permits it to continue down the chute, while the upper flange 63 is momentarily projected in front of the succeeding coin, and prevents its further 35 movement until the lower flange 62 is again in position. In this manner any desired number of coins may be retained in the chute 52, and if the front of the latter be covered with transparent material, and exposed 40 on the front of the machine, an attendant can detect the use of slugs and the like.

Having thus described my invention, what I claim and desire to secure by Letters Patent is--

1. A pencil and like marking device, including a circumferentially slotted segmental case, a turnable shaft, a fixed sleeve through which the shaft is turnable, disk 50 segments loosely mounted upon the sleeve, registering with the case slots and having keys projecting therethrough, said disks having duplicate sets of peripheral characters and said case having transverse slots 55 through which corresponding characters may be simultaneously exposed.

2. A pencil and like marking device, including a circumferentially slotted segmental case, a turnable shaft, a fixed sleeve 60 through which the shaft is turnable, disk segments loosely mounted upon the sleeve, registering with the case slots and having keys projecting therethrough, said disks having duplicate sets of peripheral characters, said case having transverse slots 65

through which corresponding characters may be simultaneously exposed, an ink pad contiguous to the characters, an inking roller, and means actuated by the oscillation of the shaft to traverse the roller over 70 the pad and one set of exposed characters.

3. A pencil and like marking device, including a circumferentially slotted segmental case, a turnable shaft, a fixed sleeve through which the shaft is turnable, disk 75 segments loosely mounted upon the sleeve, registering with the case slots and having keys projecting therethrough, said disks having duplicate sets of peripheral characters, said case having transverse slots 80 through which corresponding characters may be simultaneously exposed, an ink pad contiguous to the characters, an inking roller, means actuated by the oscillation of the shaft to traverse the roller over the pad 85 and one set of exposed characters, an impression bar movable in line with the exposed characters, and means actuated by the rotation of the shaft to impress an interposed article upon the type characters. 90

4. A pencil marking device comprising a segmental case, a shaft turnable therein, a fixed sleeve through which the shaft extends, segmental disks loosely turnable upon the sleeve, having duplicate sets of peripheral characters contiguous to the case, an inking pad, a roller movable over the pad 95 and one set of characters, arms turnable about the shaft, in which arms the roller is journaled, a fulcrumed lever adapted to engage said arm, and a cam arm movable with the shaft and engageable to actuate the lever. 100

5. A pencil marking device comprising a segmental case, a shaft turnable therein, a fixed sleeve through which the shaft extends, segmental disks loosely turnable upon the sleeve, having duplicate sets of peripheral characters contiguous to the case, an inking pad, a roller movable over the pad 105 and one set of characters, arms turnable about the shaft, in which arms the roller is journaled, a fulcrumed lever adapted to engage said arm, a cam arm movable with the shaft and engageable to actuate the lever in 110 one direction, and a spring by which the arms and roller are returned to the pad 115 when released from direct pressure.

6. A pencil marking device comprising a segmental case, a shaft turnable therein, a fixed sleeve through which the shaft extends, segmental disks loosely turnable upon the sleeve, having duplicate sets of peripheral characters contiguous to the case, an inking pad, a roller movable over the pad 120 and one set of characters, arms turnable about the shaft, in which arms the roller is journaled, a fulcrumed lever adapted to engage said arm, a cam arm movable with the shaft and engageable to actuate the lever, 125 130

an incline over which the pencils are delivered transversely above the marking character, and means to retain them in position while being impressed.

- 5 7. A pencil marking device comprising a segmental case, a shaft turnable therein, a fixed sleeve through which the shaft extends, segmental disks loosely turnable upon the sleeve, having duplicate sets of peripheral characters contiguous to the case, an inking pad, a roller movable over the pad and one set of characters, arms turnable about the shaft, in which arms the roller is journaled, a fulcrumed lever adapted to engage said arm, a cam arm movable with the shaft and engageable to actuate the lever, 10 an incline over which the pencils are delivered transversely above the marking character, means to retain them in position while 15 being impressed, an impression bar alined with the pencil position, a lug turnable with the shaft, and connecting links between the bar and lug.
- 20 8. A pencil marking device comprising a

segmental case, a shaft turnable therein, a 25 fixed sleeve through which the shaft extends, segmental disks loosely turnable upon the sleeve, having duplicate sets of peripheral characters contiguous to the case, an inking pad, a roller movable over the pad 30 and one set of characters, arms turnable about the shaft, in which arms the roller is journaled, a fulcrumed lever adapted to engage said arm, a cam arm movable with the shaft and engageable to actuate the lever, 35 an incline over which the pencils are delivered transversely above the marking characters, a carriage movable with the inking roller and having upturned stops controlling the forward movement of the pencil. 40

In testimony whereof I have hereunto set my hand in the presence of two subscribing witnesses.
